DIGITAL VOLTMETER HOUSING OR SIMILAR ARTICLE

Dale W. Gruyé, Sunnyvale, Calif., assignor to Fairchild
Camera & Instruments Corp., Syosset, Long Island,
N.Y., a corporation of Delaware

Filed Dec. 14, 1964, Ser. No. 83,027

Term of patent 14 years

(Cl. D26—1)

The single figure in the drawing is a front, top, and right side perspective view of a digital voltmeter housing or similar article, showing my new design.

The rear, bottom and left side, not shown, are substantially mirror images, respectively, of the front, top and right side shown.

I claim:

The ornamental design for a digital voltmeter housing or similar article, substantially as shown and described.
